SELECTIVE DISCHARGE CONTROL FOR
INKS ON PRINTING PRESSES

William C. Huebner, New York, N. Y.

Application August 6, 1945, Serial No. 609,269

30 Claims. (Cl. 101—426)

1

This invention relates to a process and apparatus for printing and more particularly to the method and means for selectively controlling the density or color value of the ink deposition on the print receiving material.

This application is a continuation-in-part of my application Serial No. 530,787, filed April 13, 1944, for Means and Method of Selective Control of Ink Deposition in Printing, and abandoned September 13, 1945.

The sense in which certain terms are employed herein is set forth at the outset to clarify the statement of the objects of the invention and the description and claims which are to follow and to avoid all likelihood of confusion or misunderstanding.

The terms "printing," "electronographic printing" or related terms are used herein in the same sense as in my earlier Patents 1,820,194 of October 25, 1931, and 2,224,391 of December 10, 1940, and refer to the reproduction of an image or the production of a desired design on the print receiving material by the use of electro lines of force to transfer the ink to the print receiving material and without relying on pressure to effect such transference as is usual in ordinary pressure printing. The terms "image" and "design" are employed as meaning letters, words, texts, illustrations, zones and all other representations, singly or in combination, and which are ordinarily produced on print receiving material in the printing art. The term "print receiving material or element" refers to paper, cloth or other textiles, metals and any other material capable of having produced thereon an image or design. The term "ink" is to be understood as including not only ink such as commonly used in the printing art, but also pigments, coloring matter, paints and all other flowable materials that may be employed in producing an image or design on print receiving material.

The expression "field of force" is used herein in the sense generally employed in writings on electrical phenomena to indicate the field, zone or sphere within which electrostatic forces are sufficiently active or powerful enough to effect a transference of ink from one surface to another. The expression "lines of force" similarly is employed to indicate the forces themselves acting in a definite path or direction in effecting the transference of the ink. Such "lines of force" are measurable in direction and amount and their effects, even though the theoretical

2

explanation of what produces these effects may not be entirely clear or certain.

An object of the invention is to provide a method of and means for electronographically printing whereby various densities or color values of the ink deposition can be obtained in different portions of the reproduced image on the print receiving material or whereby the ink deposition can be controlled to produce different desired designs on said material.

In printing it is ordinarily and frequently necessary to apply different densities of ink on certain areas of the print receiving material than on other areas thereof, that is, certain areas should be heavier or more solid than other areas with varying gradations between the light and heavy reproduced image areas in order to obtain commercially satisfactory printing. In my prior patents above referred to, the transference of the ink to the print receiving material is effected by passing the material through a uniform strength electro field of force and subjecting the ink to the lines of force to effect the transfer thereof. Consequently, due to the uniform strength of the electro field of force, the deposition of ink on the print receiving material is of substantially uniform density.

An object of the present invention therefore is to provide improved means and method in the art of electrostatic printing for selectively and automatically controlling the intensity of the electro lines of force, to the end that the resulting image produced on the print receiving material will have the desired density gradations of ink deposition on different areas thereof.

A further object of the invention is to provide in electronographic printing apparatus improved means for varying the volume of ink transferred to the print receiving material at selected points or areas in accordance with the requirements of the image to be reproduced thereon or in accordance with the character of the design it is desired to produce on the material.

Another object is to provide in an electronographic printing apparatus a plurality of separately and selectively controlled sets of opposed ink discharge and attraction elements and between which elements the print receiving material passes, whereby the volume of ink transferred to the print receiving material at any predetermined point within the zone of transfer may be varied or controlled to meet predetermined requirements.

Another object is to provide an electronographic printing apparatus such as referred to

in the last named object and wherein a master control drum is employed to automatically control the intensity of or to interrupt the electro field of force between the discharge and attraction elements of the separate sets of elements to thus vary the density of the ink deposition on the various areas of the reproduced image or to produce on the print receiving material a desired or predetermined design.

In multicolor printing it is desirable and commercially essential that fine uniform quality of printing be maintained throughout an entire edition. In order to obtain such fine and uniform quality, the differently colored inks, such as yellow, red, blue, emerald green, purple, black and other colors should be applied accurately as to quantity or volume if the correct balance of colors is to be obtained. It will be understood that should anyone of the component colors of the printed matter be too light or too strong an adverse result may be obtained and the uniform quality of the edition destroyed.

An object of the invention is to provide an improved method of and apparatus for multicolor printing whereby the quantity or volume of the inks or pigments deposited upon the print receiving material is so controlled as to result in producing the desired color values of the printed edition with the requisite uniform quality throughout.

Another object is to control in multicolor printing the color values over the entire width of the print receiving material whereby local areas may be accentuated where more solid color is needed for greater strength to enhance the brilliancy of that local area.

A general object of the invention is to provide an improved method of and means for electrographically printing that broadens the adaptability of this art to meet required or desired results necessary for commercial printing and give to electrographical printing an advantageous flexibility.

Further and additional objects and advantages not hereinbefore referred to will become apparent during the detailed description of several embodiments of the invention which is to follow.

Referring to the accompanying drawings,

Fig. 1 is a fragmentary vertical longitudinal sectional view through a printing couple of an electrographical printing press taken substantially on line 1—1 of Fig. 2 and embodying one form of the present invention.

Fig. 2 is a vertical transverse sectional view taken substantially on line 2—2 of Fig. 1.

Figs. 3 and 4 are views similar to Figs. 1 and 2, respectively, but illustrating a different embodiment of the present invention.

Fig. 5 is a developed view partly in end elevation and partly in section of the printing press embodying the invention and illustrated in Figs. 1 and 2 and shows the master control drum which is employed in the printing couple.

Fig. 6 is a fragmentary vertical transverse sectional view taken substantially on line 6—6 of Fig. 5 and shows an inking roller for inking of the image carrying cylinder of the couple.

Fig. 7 is a diagrammatic developed view of a portion of the circumference of the control drum shown in Figs. 5 and 6 and taken substantially on line 7—7 of Fig. 9 and also of the control circuit for one set of opposed discharge and attraction elements carried, respectively, by the image cylinder and the supporting cylinder of the printing couple.

Fig. 8 is a view of a portion of the control drum and control switch shown in Fig. 7 and is taken looking from the right hand side of Fig. 7 with the support for the control switch shown in section.

Fig. 9 is a developed fragmentary elevational view of a portion of the circumference of the control drum shown in Figs. 5 and 6 and illustrates the various positions assumed by the control switch actuating lever as the drum rotates.

Fig. 10 is a diagrammatic illustration indicating by dash lines the areas of the print receiving material on which the ink depositions are made under the control of the portion of the control drum shown in Fig. 9 and correlated to the different positions of the switch actuating lever shown in Fig. 9.

Figs. 11 and 12 are similar to Figs. 9 and 10, respectively, but illustrate a different portion of the control drum circumference and the form of design produced by said portion.

Fig. 13 is a developed partial end elevational and sectional view of the printing couple disclosed in Figs. 3 and 4 and has added thereto the master control drum and other elements of the control mechanism for controlling the intensities of the electrostatic fields of force between the discharge and attraction elements or blades of the separate sets of elements or blades.

Fig. 14 is a fragmentary vertical transverse sectional view taken substantially on line 14—14 of Fig. 13 looking in the direction of the arrows.

Fig. 15 is a diagrammatic illustration of the electrical control means employed in the embodiment of the invention shown in Figs. 13 and 14.

Fig. 15a is a diagram of portions of an electrical control circuit similar to Fig. 15 but showing a modified form of control, and

Fig. 16 is a detached detail view looking at the slotted end of one of the cylinders containing the light source in the control mechanism.

Inasmuch as the present invention may be incorporated in single or multiple unit presses; in sheet or web presses, with relief, intaglio or planographic printing plates, all as shown in my said prior Patents 1,820,194 and 2,224,391, it is deemed necessary to illustrate only a single printing station or couple, it being understood that the improvement embodying the invention is equally adaptable to multiunit presses.

In Figs. 1 and 2 a printing couple is illustrated which embodies the features disclosed in my co-pending applications Ser. Nos. 518,468 and 518-469, both filed January 15, 1944 and now Patents 2,408,143 and 2,408,144, respectively, except that the discharge and attraction elements disclosed in said applications are each in the form of a single element extending the longitudinal length of the respective cylinder within which it is mounted, while in the construction shown herein in Figs. 1 and 2 the opposed discharge and attraction elements are arranged in a multiplicity of separate or independent sets of elements located within the respective cylinders.

Referring now to Figs. 1 and 2, the vertical members of a press frame are indicated at 10 and non-rotatable sleeves 11 are supported in said members. Collars 12 are mounted on the inner ends of the sleeves 11 and said collars support antifriction bearings 13. The bearings 13 rotatably support disks 14 which form the opposite ends of the image carrying cylinder A and the supporting cylinder B. The disks 14 are provided on their circumferences with gears 15 with

said gears 15 of the cylinder A meshing with the gears 15 of the cylinder B, while the gears 15 of the latter cylinder mesh with driving gears later to be referred to. It will thus be seen that the cylinders A and B rotate in timed relation. Each disk 14 on its inner side is provided adjacent its circumference with an annular shoulder on which is secured an insulating ring 16 held against movement relative to the disk by suitable means such as the dowel pin 18. The image or plate carrying cylinder A and the supporting cylinder B are mounted on the insulating rings 16 and hence are electrically insulated from the disks 14.

The image cylinder A may be provided with a printing plate of the relief, intaglio or planographic type as desired, or it may be provided with image portions permeable to electro lines of force and non-image portions impermeable thereto all as disclosed in my said prior Patent 2,224,391. Also the cylinder A may be a plain cylinder in those instances wherein the transference of ink to the print receiving material to produce a desired design is controlled solely by the existence or non-existence of electro fields of force between the pairs of discharge and attraction elements, as will later be pointed out.

The cylinder A can be inked in any of the known and usual ways, depending upon the type of printing plate used, one such way of inking the cylinder being indicated in Fig. 6 by the inking roll 17.

The lower or supporting cylinder B will have a smooth plain surface and its function is to support the print receiving material 25 directly, as shown in my said Patent 2,408,143, or to support a feed belt (not shown in Figs. 1 and 2 but shown in Figs. 3 and 4) which in turn supports the print receiving material.

As described in my prior patents hereinbefore referred to, the electro lines of force passing between the discharge and attraction blades or elements, later to be described and located within the cylinders A and B, respectively, act to transfer the ink from the image areas of the cylinder onto the print receiving material passing between the cylinders A and B and moving in timed relation thereto.

Extending through the center of each of the cylinders A and B is a hollow insulator tube 38, supported in the sleeves 11. Straddling each tube 38 at relatively closely spaced intervals substantially the length of each cylinder is a series of U-shaped magnet cores 39. These magnet cores are centered by and slideable with respect to the corresponding tube 38 and are adjustable radially of the cylinders by means of the adjusting screws 31 which are swiveled in a supporting plate 40 supported in turn by the tube 38. Each magnet core 39 is provided with right and left windings or spools 42 and all of the windings or spools are connected to a suitable source of electric current as will be well understood and as is disclosed in my hereinbefore mentioned Patent 2,224,391.

Although the magnet windings in both cylinders A and B are stated at this time to be connected to the same source of electric current, it will be pointed out hereinafter that the magnet windings in cylinder A need not be energized while the separate magnet windings in the supporting cylinder B can be variably energized to create magnetic fields of different intensities which will act to transfer the ink from the printing cylinder A to the print receiving material in

such manner as to produce ink deposition of various densities on the material.

As shown in Fig. 2 the magnet spools in cylinder A are aligned with the magnet spools in cylinder B and are arranged in vertical pairs with a north pole or spool in the cylinder A disposed opposite a south pole or spool in the cylinder B, and correspondingly a south pole or spool of cylinder A opposite a north pole or spool of cylinder B.

Specially shaped field bars 44 are secured to the ends of the respective sets of ends of the magnet cores 39 and are provided with arcuate outer surfaces 45 disposed closely adjacent the inner surface of the corresponding cylinder with the respective adjacent edges of the field bars located closely together along a line extending lengthwise of the cylinders.

Secured to the insulator tube 38 in the cylinder A and arranged lengthwise of said tube is a series of slightly separated relatively narrow blade sections or segments 35 constituting separate discharge elements. Similarly the tube 38 in the supporting cylinder B is provided with a series 25 of slightly separated relatively narrow blade sections or segments 47 constituting separate attraction elements. Said blade sections extend radially of the respective cylinders and have in this instance sharp or knife-like edges disposed 30 opposite each other and as shown terminating closely adjacent the inner surfaces of the respective cylinders at the printing zone, it being remembered that the two cylinders are slightly spaced apart so that there is no mechanical pressure or contact between the cylinders and in the 35 illustration no mechanical pressure or contact between the cylinder A and the print receiving material 25 when the latter is passing between the cylinders.

40 It will be understood that the width of the blades 35 and 47 and therefore the number of said blades may be varied in accordance with the nature of the printing to be produced on the print receiving material.

45 Also secured to each of the insulator tubes 38 and extending radially therefrom on each side of the respective sectional or segmental blades 35 and 47 between said blades and corresponding magnet spools are insulating shields or plates 70 which extend throughout the length of the series 50 of blades.

The blade sections or segments are each electrically connected with an independent wire or conductor 49 and all of said wires or conductors 55 for a set or series of the blades will lead to the exterior of the cylinder through the insulator tube 38. The respective sets of conductors are connected to a control mechanism one form of which is illustrated in Figs. 6 to 12 inclusive and 60 will later be explained.

As clearly explained in my prior Patents 1,820,194 and 2,224,391 the discharge and attraction elements, i. e., the blades, when connected with a source of high potential electric energy, 65 produce an electro field of force extending between the elements and acting to transfer the ink from the cylinder A to the print receiving material. As already stated, the magnet spools or windings are so arranged that north and south 70 poles are disposed radially opposite each other in the two cylinders. With this arrangement the magnetic lines of force parallel those of the electronographic lines of force and in close proximity thereto and form shields on each side of the 75 electronographic lines of force, thus preventing

or at least minimizing any tendency to spread or disperse that the electronographic lines of force might otherwise have and thereby insuring a more sharply defined and clear cut reproduction of the image on the print receiving material.

The insulator shields 70 serve both to prevent dissipation of the electrical energy supplied to the discharge and attraction blades or elements and to prevent the magnetic fields from distorting the electronographic fields of force. Where relatively high voltages are used to supply the attraction and discharge blades and particularly when the magnetic field is employed, the insulator shields 70 will preferably be used as shown and described. However, the magnets may be omitted in some instances and in such case the insulator shields 70 may also be omitted.

In commercial printing, as previously mentioned, certain portions of the reproduction may require a greater or heavier concentration or deposition of ink than other areas thereof consequently it is proposed to vary the voltages of the currents supplied to the different sets of discharge and attraction blades 35 and 47 in correlation to the densities of the ink deposition to be made on the print receiving material. Inasmuch as the width of the blades of the sets of blades is relatively narrow various relatively narrow fields of force of different intensities can be produced thus providing selective control of the deposition of the ink when actual printing of texts on irregular images is being performed or spot or area control when the deposition of ink is to produce a desired design and the ink has been applied over the entire surface of the cylinder A. Although the blades of each series are shown as slightly spaced apart, it will be understood that the transferred ink will have a certain spread and the printing produced will not indicate the spaces shown between the blades.

A mechanism for controlling the intensities of the fields of force produced by the sets of discharge and attraction elements will now be explained with particular reference to Figs. 5 to 12 inclusive. As previously stated, the gears 15 of the cylinder B mesh with driving gears and reference to Fig. 5 discloses said driving gears 19 as mounted on a driving shaft 20 that is actuated by a suitable power source not shown. The frame members 10 rotatably support below the shaft 20 a master control drum 21 which is provided on its opposite ends with gears 22 that constantly mesh with the gears 19. Although the axis of the control drum is shown in vertical alignment with the axes of the cylinders A and B and shaft 20, it will be understood that this relationship can be varied if desired, as, for instance, to reduce the height of the press. The cylinders A and B and the drum 21 rotate in timed relation to each other with the cylinder A rotating in a counterclockwise direction as viewed in Fig. 6 and the cylinder B and drum 21 in a clockwise direction.

The drum 21 is divided longitudinally thereof into zones correlated in number to the sets of discharge and attraction elements in the cylinders A and B. Each zone of the drum 21 is in the form of a circular groove formed in the drum and is provided with a series of circumferentially spaced openings 23. The openings 23 are adapted to receive pins formed on cam blocks 24 and said pins are held in the holes 23 in any desired or well known manner. The cam blocks 24 are of such width that they interfit the zone grooves and consequently are held against turning movement (see Figs. 7 and 8). The different cam blocks 24 are provided with different shaped camming portions

and said cam blocks are mounted in the zone grooves in correlation to the image that is to be reproduced on the print receiving material or to a desired design that is to be produced thereon, as will later be readily understood.

5 The supporting bar 25 is carried by the frame members 10 and extends longitudinally of the control drum 21 and carries a series of control switches 26, there being as many control switches 10 as there are grooved zones on the drum 21, see Fig. 5.

15 The control switches 26 are illustrated merely by way of example as having two "on" positions and an intermediate or "off" position, it being understood that a different form of switch might be employed if desired to meet certain conditions. The switch 26 is illustrated as comprising two spaced contacts 27 and 28 and an arcuate wiper contact 29. A switch bar 30 is constantly in contact with the wiper 29 and can be selectively engaged with the contacts 27 or 28 or can be positioned intermediate said contacts 27 and 28 when the switch is in its "off" position.

20 The switch bar 30 is insulated from but carried by a rockable lever arm 32 that is pivotally mounted on the support 25 and extends radially toward the control drum 21 as viewed in Figs. 6 and 8, with the end of the lever arm cooperating with the cam block 24. It will be seen that as the control drum 21 rotates and the lever arm 32 comes into engagement with one of the cam blocks 24 said cam block can effect a rocking movement of the lever arm to position the switch plate 30 in either one of the two "on" positions 35 or in the intermediate "off" position.

25 Each attraction blade 47 is electrically connected by a wire 33 to the wiper contact 29 of its correlated switch 26 as clearly shown in Fig. 7. Each discharge element 35 is electrically connected by a wire 34 to one side of a source of high potential electric energy. The other side of said source of electric energy is represented by the wire 36 which is electrically connected to the adjustable wiper arms 37 of a pair of rheostats 41 30 and 43. The resistance 46 of the rheostat 41 is electrically connected by a wire 48 to the contact 28 of the switch 26. The resistance 50 of the rheostat 43 is electrically connected by a wire 51 to the contact 27 of the switch 26.

35 As shown in Fig. 7 the wiper arm 37 of the rheostat 41 is positioned to cut out the resistance 46 from the circuit, wherefore said resistance does not reduce the intensity of the current in the circuit in this instance and full source current can pass between the discharge and attraction elements 35 and 47 when the switch bar is contacting the contact 28.

40 It will also be noted by reference to Fig. 7 that the wiper arm 37 on the rheostat 43 is positioned to include a portion of the resistance 50 in the circuit between the discharge and attraction elements when the switch bar 30 is engaging the contact 27 of the switch 26 and hence the intensity of the current in the circuit will be reduced a predetermined amount.

45 It will be understood that when the switch bar 30 is in the intermediate position between the switch contacts 27 and 28 no induced current will be flowing between the discharge and attraction elements 35 and 47 in this particular instance.

50 Assuming that the entire exterior surface of the cylinder A is inked by the inking roller 17 in a manner well known in the art and that a desired design is to be produced on the print receiving material 25 the cam blocks 24 correlated to each

set of discharge and attraction elements are positioned in a predetermined manner circumferentially of the drum to control the circuits to the respective sets of discharge and attraction elements so as to provide in this instance a circuit of high intensity, a circuit of low intensity or to interrupt the circuit.

In Fig. 9 there is illustrated in a developed manner one groove zone of the control drum 21 with the cam blocks 24 arranged therein in said predetermined manner. Assuming that the printing couple is operating and the control drum is rotating in the direction of the arrow in Fig. 9 and referring to the lowermost cam block 24 in said view, it will be noted that the end of the lever arm 32 is in its most left hand position before it contacts with said lowermost cam block 24. Therefore the switch bar 30 is engaging the contact 28 of the switch 26 and consequently the induced current between the discharge element 35 and the attraction element 47 is of maximum intensity and the deposition of ink on the print receiving material at this moment will be of heavy density or color and will produce a heavy color zone on the material represented by the lowermost dash line outline of Fig. 10 and which for illustration purposes parallels the groove control zone of Fig. 9.

As the control drum rotates in the direction of the arrow the end of the lever arm 32 engages the cam surface of the lowermost cam block and is moved toward the right until it is in its extreme right hand position. This movement of the lever arm 32 causes the switch bar 30 to move off of the contact 28 and momentarily into a position intermediate the contacts 28 and 27, at which time the circuit through the discharge and attraction elements is momentarily interrupted and then to move into engagement with the contact 27, whereupon the circuit is reestablished but at a lower intensity. Consequently there will be a space on the print receiving material on which no ink deposit will be made and then the ink deposition will be resumed with a light deposit. During the further rotation of the drum the lever arm 32 stays in the position to which it has been moved and the light deposition of ink continues to be made on the print receiving material as indicated in Fig. 10 by the elongated dash line outline marked "light." As the drum continues to rotate the end of the lever arm 32 engages the camming surface of the next cam block 24 which is spaced circumferentially from the first mentioned cam block and said lever arm is rocked by the second cam block to its intermediate position, at which time the circuit to the discharge and attraction elements is interrupted and consequently no ink deposit is made on the print receiving material. As the drum 21 continues to rotate the camming surface of the third circumferentially spaced cam block 24 engages the end of the lever arm 32 and moves said end of the arm from its intermediate position to its most left hand position, whereupon the switch bar 30 again engages the contact 28 and the high intensity circuit between the discharge and attraction elements is restored and a heavy ink deposit is now being made on the print receiving material, as indicated by the dash line outline at the upper end of Fig. 10.

It will be understood that the cam blocks can be so positioned as to vary the path which the end of the lever arm 32 will follow during the relative rotation between the drum and the lever arm so as to selectively produce predetermined heavy

or light ink depositions on the print receiving material or areas where no ink is deposited.

Figs. 9 and 10 as already explained indicate one arrangement of the cam blocks for producing a predetermined design of ink deposit on the print receiving material, while Figs. 11 and 12 represent a different arrangement which can be employed as will be clearly understood. It will be understood that the cam blocks will be arranged in this predetermined manner in all of the groove zones of the control drum so as to control simultaneously the transference of ink between the discharge and attraction elements of all of the sets of said elements and thereby produce the desired design on the print receiving material extending the width thereof.

In place of the switches 26 being of the type to provide two "on" positions and an "off" position, said switches can be of different type so as to provide a different number of "on" and "off" positions as desired according to the desired design that is to be produced on the print receiving material but for the sake of simplicity only a three-position switch has been illustrated herein.

The description just above given refers to the production of a desired design on the print receiving material as indicated in Figs. 10 and 12 and when the drum A is entirely permeable to the electro lines of force. The present invention can also be employed when the drum A is provided with a predetermined image that is to be reproduced on the print receiving material as, for example, when the drum A is constructed as in my prior Patent 2,224,391 with image areas permeable to lines of force and non-image areas impermeable thereto.

When a predetermined image is to be reproduced on the print receiving material the intensity of the induced electro lines of force between the discharge and attraction elements of each set can be controlled in a manner somewhat similar to that previously described herein to cause the ink deposit corresponding to certain image areas or to certain portions of certain image areas to be of different degrees of density, i. e., heavy, light or intermediate shades. In such case the control switches used would have a number of positions corresponding to the number of shades desired, it being understood that the outline of the reproduced image would be attained by the outline of the permeable image portions of the drum.

It will also be understood that the present invention can be employed to control the color shades of the reproduced image when the drum A is provided with a printing or image plate of either the intaglio, relief or planographic type as will be apparent to one skilled in the printing art.

In describing hereinafter another embodiment of the invention a more detailed description as to how the invention is adaptable for controlling the color shades of the reproduced image will be set forth.

Referring now to the embodiment of the invention shown in Figs. 3 and 4, the selective control of the intensity of the lines of force throughout the length of the field is illustrated as incorporated in that type of printing apparatus shown in my copending application Serial No. 518,470, filed January 15, 1944, now Patent 2,451,288, wherein the ink is transferred from the discharge blade or element directly to the print receiving material and without intervening

application of the ink to an image carrying plate or surface. Also in said Patent 2,451,288 the supporting cylinder for the print receiving material or the conveyor belt acts as the image or printing cylinder and is provided with image portions permeable to the electro lines of force and non-image portions impermeable thereto, wherefore the ink is transferred to the print receiving material only in those areas correlated to the permeable image portions of the cylinder.

In Figs. 3 and 4 the cylinder A' is the printing or image cylinder and preferably is constructed and mounted in the frame as in the previously described construction of the cylinders A or B. The cylinder A' is adapted to be driven from any suitable source of power as by the shaft 90, pinions 91 and gears 15, while the paper or other print receiving material 86 is conveyed by a belt 82 as in my said Patent 2,451,288.

As in the construction of the press shown in Figs. 1 and 2 the attractor blades within the cylinder A' comprise a series of sections or segments 147 with individual conductors 149 leading to the control mechanism later to be described. As shown, the blade sections are mounted on an insulator tube 92 vertically slidably guided by and adjustable on the insulator tube 138 by means of the adjusting screws 192, whereby the spacing between the knife edges of the sectional attractor blades 147 and the surface of the cylinder may be regulated. The sectional discharge or repulsion blades 135 are constructed similarly to the attractor blades, with the individual conductors 52 for the blade sections leading to the control mechanism later to be explained.

A controlled and conditioned supply of ink to the discharge blades 135 is provided in the following manner. If all of the discharge blades are to receive ink of the same color a longitudinally extending container 125 may be used, with said container in turn supplied through the supply pipe 126. The container 125 may have a series of nozzles 130 projecting downwardly from the bottom thereof and corresponding in number and correlated to the discharge blades 135. Each nozzle is provided with a control valve 131 and the ink from each nozzle is disposed on an inclined plate 170 and flows downwardly of the plate and onto the respective discharge blade 135. To insure a steady and uniform flow through the nozzles air pressure may be employed, the air being admitted to the container 125 through the pipe 133. Also in order to regulate the fluidity of the ink strip electric heaters 137 may be secured to the underside of the plates 170, as described in my said Patent 2,451,288. It will be understood that in certain instances it will be desirable to have the different discharge blades 135 receive ink of different colors and in such cases instead of a single container 125 for all of the discharge blades 135 individual containers for each discharge blade may be employed.

Referring now to Figs. 13 to 16 inclusive, the mechanism for selectively and automatically controlling the intensities of the fields of force between the opposed discharge and attraction elements of the sets of said elements will now be described. The pinions 191 mesh with gears 53 on the opposite ends of a master control drum 54 which is rotatable on a shaft 55 fixedly secured in the frame members. Although the drum 54 is illustrated in Figs. 13 and 14 as in vertical alignment with the axis of the cylinder

A' and shaft 90 it will be understood that the axes of the drum, cylinder and shaft could be displaced from this vertical relationship if it were desired to lower the height of the printing press. The control drum 54 will have secured on its periphery by suitable means a master sheet containing a chart correlated to the image to be reproduced on the print receiving material. It will also be understood that where the image is reproduced in different colored ink the chart will have differently colored portions correlated to the different colored ink containers and the sets of blades associated with said containers.

The side frame members of the printing apparatus support on opposite sides of the shaft 90 bars 56 extending between the frame members and provided with a series of openings corresponding in number to the sets of discharge and attraction blades and with each opening aligned with a respective set of blades, as shown in Figs. 13 and 14. The openings in one of the bars 56 mount housings 57 for light sources 58 of any suitable known form, while the openings in the other bar 56 mount housings 59 for photoelectric cells 60. The housings 57 and 59 are in the illustration disposed substantially at an angle of 45° to the vertical center line of the press, although they might be otherwise disposed. The housings 57 are provided at their lower ends with cover plates having slots 61 extending diametrically thereof parallel to the axes of the master drum 54 and cylinder A' and corresponding in length to the width of the blade sections (see Figs. 14 and 16). The housings 59 mount condensing lenses 62 which act to condense the light beams reflected from the surface of the master sheet to the photoelectric cells 60. The light beams from the light sources striking the master sheet correspond in width to the width of the blade sections and said beams are reflected in varying degrees of strength according to the density of color upon which they impinge on the master sheet. Therefore the strengths of the reflected beams acting on the photoelectric cells are in inverse proportion to the density of the color on the different portions of the master sheet by which the beams are reflected. Therefore the intensities of the induced electro fields of force between the different sets of discharge and attraction blades can be controlled in relation to the different color densities on the various areas of the master sheet as the sensitivity of the photoelectric cells will effect through an amplifying arrangement later to be described a control of the separate electrical circuits for the sets of blades. Similar light sources and photoelectric cells are employed which scan the ink deposit on the print receiving material and cause the strength of the light beams reflected to the photoelectric cells to be in inverse proportion to the color densities of the ink deposited on the material. The duplicate series of light sources and photoelectric cells are located on opposite sides of the series of discharge blades 135 and above the print receiving material. The supporting bars for the duplicate series of light sources and photoelectric cells are indicated at 56a, while the housings therefor are indicated at 57a and 59a, with the light sources indicated at 58a and the photoelectric cells at 60a. The housings 57a will be provided at their lower ends with cover plates having slots 61a therein while the housings 59a will be provided with condensing lenses 62a.

Referring to Figs. 13 and 14, containers 63 shown as located below the drum 54 house the amplifying circuits and devices with which each set of photoelectric cells 60 and 60a is operatively associated, there being one container 63 for each set of discharge and attraction blades. The amplifying circuits referred to effect forward and reverse energization of special split phase reversing motors 64 supported by the containers externally thereof. It will be understood that the motors 64 correspond in number to the number of opposed sets of discharge and attraction blades and that said motors are arranged for convenience in two series with the motors related to the even numbered sets of opposed blades located on one side of the containers 63 and the motors related to the odd numbered sets of opposed blades located on the opposite side of the containers. Each motor shaft 65 extends upwardly and is provided with a worm 65a which meshes with a worm wheel 66 mounted on the shaft 67 of a rheostat later to be referred to.

Referring to the diagrammatic showing of Fig. 15, the rheostat referred to includes a resistance 68 and a wiper hand 69 mounted on the shaft 67 and contacting the resistance 68, wherefore rotation of the shaft 67 by the motor 64 (operatively connected therewith as indicated by dash and dot lines) varies the position of the wiper hand relative to the resistance as will be well understood. One terminal of the resistance 68 is connected by a wire 71 to one side of a source of high potential electric energy, while the other side of said source is connected to the attraction blade 147 by the wire 149 previously referred to. The discharge blade 135 is electrically connected by the previously mentioned wire 52 with the wiper hand 69 of the rheostat. Consequently the intensity of the current in the circuit to the blades 135 and 147 can be varied by the adjustment of the wiper hand 69 and thus the intensity of the induced electrostatic field of force between said blades can be varied to change the density of the ink deposition on the print receiving material. It will be understood that the intensity of the induced field of force between each set of opposed discharge and attraction blades is similarly controlled by a rheostat actuated by a motor 64. The wires 52 and 149 and the wires, later referred to, forming the photoelectric cell circuits extend through openings in a frame member 10 and into a cover 10a (see Fig. 13) and thence to the container 63 and the rheostats.

The forward or reverse operation and the stopping of each motor 64 is controlled in the manner now to be described.

The photoelectric cells 60 and 60a correlated to each set of opposed discharge and attraction blades or elements are connected in series parallel to wires 72 and 73. A control tube 74 is in the direct current circuit indicated generally at 75 and said circuit is connected to any suitable source of regulated voltage direct current. The wire 72 is connected to one grid of the tube 74 while the wire 73 is connected to the other grid of said tube. As long as the photoelectric cells 60 and 60a are activated by reflected light beams of equal intensity and are thus in balance no current is passing through the control tube 74 to the amplifying tubes 76 and 77. However, when the reflected light beam activating one of the photoelectric cells is stronger than the beam activating the other cell then one of the grids of 75

the control tube 74 is activated more strongly than the other grid and current flows from said grid through the tube 74 to an amplifying tube connected to the grid circuit. Consequently any unbalanced condition in the photoelectric cells 60 and 60a will operate through the control tube 74 to activate either the amplifying tube 76 or the amplifying tube 77. It will be understood that so long as the light beams reflected by the master sheet on the control drum and by the ink deposit on the print receiving material are of the same intensity the cells 60 and 60a are in balance and the amplifying tubes 76 and 77 are not driven. The amplifying tube 76 may be termed the reverse amplifying tube while the tube 77 may be designated as the forward amplifying tube. It will be further understood that as soon as the reflected light beams vary in intensity and create an unbalanced condition between the cells 60 and 60a then either the reverse tube 76 is driven or the forward tube 77, depending upon which photoelectric cell has the stronger output.

The reverse amplifying tube 76 is connected to 25 the primary of a saturable reactor 78 while the forward amplifying tube 77 is connected to the primary of a saturable reactor 79. The secondaries of the reactors 78 and 79 are connected respectively to the shaded poles or windings 80 and 81 of the motor 64. These poles or windings 80 and 81 act as small transformer secondaries and have voltage induced therein from the field winding 83 of the motor and which winding 83 is continuously excited from an outside alternating current source 84. The alternating current source 84 has the primary of a transformer 85 connected thereto, while the secondary of such transformer supplies current to the filaments of the tubes 74, 76 and 77.

So long as the photoelectric cells 60 and 60a are in balance and no current is flowing through the control tube 74 to the amplifying tube 76 or the amplifying tube 77 the induced voltages in the poles or windings 80 and 81 by the winding 83 are in balance and cause no rotation of the motor 64. As soon as an unbalanced condition exists between the photoelectric cells 60 and 60a and the grid of the tube 76 or the grid of the tube 77 is activated and either the reactor 78 or the reactor 79 becomes active then the induced voltages in the windings or poles 80 and 81 are unbalanced and a current flow takes place in one or the other of said windings to effect rotation of the motor 64 in either the reverse or forward direction. As previously explained, the rotation of the motor 64 in the forward or reverse direction will act through the rheostat and wiper hand 69 to decrease or increase the current to the discharge and attraction blades 135 and 147 to thereby decrease or increase the intensity of the induced electrostatic field of force between said blades and thus to decrease or increase the density of the ink deposit on the print receiving material.

It will be understood that as soon as the density of color of the ink deposit corresponds to the density of the color on the correlated portion of the master sheet on the control drum the photoelectric cells are in balance and rotation of the motor 64 ceases and no further change in the current value to the discharge and attraction blades takes place until said color densities again vary. In this way an accurate control of the ink densities of the ink deposit on the print receiving material is maintained and an accurate

reproduction of the color values on the master control sheet is obtained on the print receiving material.

Although the series of photoelectric cells 60a has been illustrated and described as scanning the ink deposit on the print receiving material, it is possible to eliminate the series of cells 60a and light sources therefor and rely only upon the series of cells 60 and their light sources which scan the master sheet of the control drum and commercial printing can be obtained by this modified arrangement.

Reference to Fig. 15a will indicate a simple way in which the control circuit shown in Fig. 15 could be modified to eliminate the photoelectric cell 60a and still effectively control the density of the ink deposit on the print receiving material in correlation to the color densities on the master sheet. In Fig. 15a a variable resistance is connected between the wires 72 and 73 in place of the photoelectric cell 60a.

The variable resistance comprises a resistance coil 60b connected to the wire 72 and a wiper hand 60c connected to the wire 73 and cooperating with the resistance coil 60b. The variable resistance controls the function of the grid of the control tube 74 that is controlled by the photoelectric cell 60a in the diagram shown in Fig. 15, while the photoelectric cell 60 in both instances controls the other grid of the control tube 74. The wiper hand 60c of the variable resistance is operatively interlocked with the wiper hand 69 of the rheostat that controls the high potential electric circuit to the discharge and attraction blades indicated by the dash and dot line in Fig. 15a, wherefore the wiper hands 69 and 60c move in unison and have inverse relative positions with respect to the resistances 68 and 60b.

When the variable resistance just described is placed in the circuit instead of the photoelectric cell 60a the control tube 74 functions in the same way as in the circuit shown in Fig. 15 to control the flow of current to either the reverse amplifying tube 76 or the forward amplifying tube 77 to effect reverse or forward rotation of the motor 64. It will be seen that when the current value flowing through the variable resistance is in balance with the output current value of the photoelectric cell 60 the motor 64 is not rotating. When the reflected light beam on the photoelectric cell 60 causes the output current value of said cell to be above the current value flowing through the variable resistance, the grid of the tube 74 connected with the photoelectric cell predominates over the other grid of said tube and current flows through the amplifying tube 77 to effect forward rotation of the motor 64 to operate the wiper hand 69 of the rheostat to increase the resistance and reduce the high potential electric current intensity to the discharge and attraction blades and to cause a less dense ink deposition on the print receiving material, it being recalled that the wiper hand 69 is mechanically interlocked with the wiper hand 60c of the variable resistance. It will be seen that the wiper hand 60c will also be moved by the rotation of the motor 64 to cut out resistance until the current value flowing through the variable resistance steps up until it is in balance with the output current value of the photoelectric cell 60, whereupon the motor stops. A similar sequence takes place when the output current value of the cell 60 becomes less than the current value flowing through the variable resistance, such condition occurring when the reflected light

beam acting on the photoelectric cell 60 is reduced in strength. When this happens the grid of the control tube 74 connected to the variable resistance is activated to cause current to flow through the amplifying tube 76 and effect reverse rotation of the motor 64 to move the wiper hand 69 of the rheostat to cut out resistance and thus to increase the intensity of the high potential electric current to the discharge and attraction blades to effect a heavier deposition of ink on the print receiving material. Simultaneously with the movement of the wiper hand 69 the wiper hand 60c of the variable resistance moves to increase the resistance and thus decrease the current value flowing to the grid of the tube 74 connected with said resistance until said grid is in balance with the grid connected to the photoelectric cell 60, whereupon the rotation of the motor 64 terminates.

From the foregoing explanation in connection with Fig. 15a it will be seen that the one series of photoelectric cells scanning the master sheet on the control drum can effectively control the deposition of ink on the print receiving material in coordination with the color values on the master sheet.

As previously stated herein the magnets in the cylinder A of Figs. 1 and 2 could be eliminated and the magnets in cylinder B utilized to produce magnetic fields of force acting to transfer the ink from the cylinder A to the print receiving material as fully disclosed in my said Patent 2,224,391. It will be clearly understood that the individual electromagnets in the cylinder B as shown in Figs. 1, 2 and 6 each could be connected by a separate circuit to a source of electrical energy and that the current value of each of such circuits could be controlled to create magnetic fields of varying intensities to control the densities of the ink deposition on the print receiving material. The control of the current values of these separate circuits could be carried out in ways similar to the methods disclosed herein for controlling the intensities of the electrostatic fields of force between the discharge and attraction blades as will be clear to one skilled in the art.

Therefore the present invention contemplates printing by means of a plurality of separate magnetic fields of force the intensities of which are automatically controlled to produce ink deposits on the print receiving material of predetermined densities.

From the foregoing description it will have been seen that an extremely flexible and efficient printing couple results from the use of the present invention and one wherein the volume of ink transferred by the electro fields of force can be controlled to produce ink deposits of predetermined densities on the print receiving material. It will also be noted that the present invention lends itself admirably to a single printing couple capable of producing multicolor printing and wherein the desired and necessary color values can be maintained throughout an entire edition.

Although a number of embodiments of the invention have been illustrated and described herein it will be understood that the invention is susceptible of various modifications and adaptations within the scope of the appended claims.

Having thus described my invention, I claim:

1. A method of printing by utilizing an electro field of force and which comprises passing print receiving material through a printing zone and moving a master chart in timed relation to said

material, producing by means of an applied electric current a field of force at the printing zone with the lines of force directed to transfer ink from an ink supply to said material, and varying said current to vary the intensity of said field of force in correlation to said master chart as said material moves through said zone to predeterminately vary the densities of the ink deposits on different areas of said material to produce a printed image or design having varying color shades or densities on different portions thereof as indicated by said master chart.

2. A method of printing by utilizing an electro field of force which comprises passing print receiving material through a printing zone and moving a master chart in timed relation to said material, producing by means of applied electric currents a plurality of separate fields of force at the printing zone and extending transversely of said material with the lines of force of each field of force directed to transfer ink from an ink supply to said material, and varying said currents to vary the intensities of said separate fields of force in correlation to said master chart as said material moves through said zone to predeterminately vary the densities of the ink deposits on different areas of said material to produce a printed image or design having varying densities or varying color effects on different portions thereof as indicated by said master chart.

3. A method of printing by utilizing an electro field of force and which comprises passing print receiving material through a printing zone and moving a master chart in timed relation to said material, producing by means of an applied electric current a field of force at the printing zone with the lines of force directed to transfer ink from an ink supply to said material, and maintaining the densities of the ink deposits on different areas of said material in balance with the color densities on different areas of said chart correlated thereto by varying said current to vary the intensity of said field of force.

4. A method of printing by utilizing an electro field of force which comprises passing print receiving material through a printing zone and moving a master chart in timed relation to said material, producing by means of applied electric currents a plurality of separate fields of force at the printing zone and extending transversely of said material with the lines of force of each field of force directed to transfer ink from an ink supply to said material, and maintaining the densities of the ink deposits on different areas of said material in balance with the color densities on different areas of said chart correlated thereto by varying said currents to vary the intensities of said separate fields of force.

5. A method of printing by utilizing an electro field of force which comprises passing print receiving material through a printing zone and moving a master chart in timed relation to said material, producing a plurality of separate electrostatic fields of force at the printing zone and extending transversely of said material with the lines of force of each field of force directed to transfer ink from an ink supply to said material, and varying the intensities of said separate fields of force in correlation to said master chart as said material moves through said zone to predeterminately vary the densities of the ink deposits on different areas of said material to produce a printed image or design having varying densities or varying color effects on different portions thereof.

portions thereof as indicated by said master chart.

6. A method of printing by utilizing an electro field of force and which comprises passing print receiving material through a printing zone and moving master control means in timed relation to said material, producing by means of an applied electric current a field of force at the printing zone bridging a predetermined gap with the lines of force directed to transfer ink across said gap from an ink supply to said material, and varying said current to vary the intensity of said field of force in correlation to said control means as said material moves through said zone to predeterminately vary the densities of the ink deposits on different areas of said material to produce a printed image or design having varying color shades or densities on different portions thereof and correlated to said control means.

7. A method of printing by utilizing an electro field of force which comprises passing print receiving material through a printing zone and moving a master control means in timed relation to said material, producing by means of applied electric currents a plurality of separate fields of force at the printing zone and extending transversely of said material with the lines of force of each field of force directed to transfer ink from an ink supply to said material, and varying said currents to vary the intensities of said separate fields of force in correlation to said control means as said material moves through said zone to predeterminately vary the densities of the ink deposits on different areas of said material to produce a printed image or design having varying densities or varying color effects on different portions thereof and correlated to said control means.

8. A method of printing by utilizing an electro field of force and which comprises passing print receiving material through a printing zone and moving a master control means in timed relation to said material, producing by means of an applied high potential electric current an electrostatic field of force at the printing zone with the lines of force directed to transfer ink from an ink supply to said material, and varying the potential of said current to vary the intensity of said field of force as said material moves through said zone and in correlation to said control means to predeterminately vary the densities of the ink deposits on different areas of said material to produce a printed image or design having varying color shades or densities on different portions thereof.

9. A method of printing by utilizing an electro field of force which comprises passing print receiving material through a printing zone and moving a master control means in timed relation to said material, producing by means of applied high potential electric currents a plurality of separate electrostatic fields of force at the printing zone and extending transversely of said material with the lines of force of each field of force directed to transfer ink from an ink supply to said material, and varying the potentials of said currents to vary the intensities of said separate fields of force in correlation to said control means as said material moves through said zone to predeterminately vary the densities of the ink deposits on different areas of said material to produce a printed image or design having varying densities or varying color effects on different portions thereof.

10. A method of printing by utilizing an electro field of force which comprises passing print receiving material through a printing zone and moving a master control means in timed relation with said material, producing by means of applied high potential electric currents a plurality of separate electrostatic fields of force at the printing zone extending transversely of said material with the lines of force of each field of force directed to transfer ink from an ink supply to said material, restricting the effective width of said fields of force by producing magnetic fields of force closely adjacent to and paralleling each side of said electrostatic fields of force, and varying the potentials of said currents to vary the intensities of said separate electrostatic fields of force in correlation to said control means as said material moves through said zone to predeterminedly vary the densities of the ink deposits on different areas of said material to produce a printed image or design having varying densities or color effects on different portions thereof.

11. In a printing couple, ink carrying means, means for moving print receiving material relative to said ink carrying means and through the printing zone, means for producing by an electric current an electro field of force at the printing zone with the lines of force thereof acting in a direction to transfer ink from said ink carrying means to said material, and means correlated to the movement of said material for automatically varying said current to vary the intensity of said field of force as said material moves through the printing zone to produce ink deposits on said material of predetermined varying densities.

12. In a printing couple, ink carrying means, means for moving print receiving material relative to said ink carrying means and through the printing zone, a plurality of means for producing by electric currents separate electro fields of force at the printing zone, with the lines of force of each of said fields of force acting in a direction to transfer ink from said ink carrying means to said material, and separate means correlated to the movement of said material for automatically individually varying said currents to vary the intensities of each of said fields of force as said material moves through the printing zone to produce ink deposits on said material of predetermined varying densities.

13. In a printing couple, ink carrying means, means for moving print receiving material relative to said ink carrying means and through the printing zone, a master control member movable in timed relation to the movement of said material through the printing zone, means for producing by an electric current an electro field of force at the printing zone with the lines of force thereof acting in a direction to transfer ink from said ink carrying means to said material, and means operatively controlled by said control member for varying said current to vary the intensity of said field of force as said material moves through the printing zone to produce ink deposits on said material of predetermined varying density and correlated to said control member.

14. In a printing couple, ink carrying means, means for moving print receiving material relative to said ink carrying means and through the printing zone, a master control member movable in timed relation to the movement of said material through the printing zone, a plurality of separate means for producing separate electro fields of force at the printing zone with the lines of force of each field of force acting in a direction to

transfer ink from said ink carrying means to said material, and separate means operatively controlled by said control member for varying the intensities of said separate fields of force as said material moves through the printing zone to produce ink deposits on said material of predetermined varying densities correlated to said control member.

15. In a printing couple, ink carrying means, means for moving print receiving material relative to said ink carrying means and through the printing zone, a master control member movable in timed relation to the movement of said material through the printing zone, means for producing by an electric current an electrostatic field of force at the printing zone with the lines of force thereof acting in a direction to transfer ink from said ink carrying means to said material, and means operatively controlled by said control member for varying said current to vary the intensity of said field of force as said material moves through the printing zone to produce ink deposits on said material of predetermined varying densities correlated to said control member.

16. In a printing couple, ink carrying means, means for moving print receiving material relative to said ink carrying means and through the printing zone, a master control member movable in timed relation to the movement of said material through the printing zone, separate means for producing a plurality of separate electrostatic fields of force at the printing zone with the lines of force of each field of force acting in a direction to transfer ink from said ink carrying means to said material, and separate means operatively controlled by said control member for varying the intensity of each of said fields of force as said material moves through the printing zone to produce ink deposits on said material of predetermined varying densities.

17. In a printing couple, ink carrying means, means for moving print receiving material relative to said ink carrying means and through the printing zone, separate means for producing by electric currents a plurality of separate electro magnetic fields of force at the printing zone with the lines of force of said field of force acting in a direction to transfer ink from said ink carrying means to said material, and means correlated to the movement of said material for automatically varying said currents to vary the intensities of said fields of force as said material moves through the printing zone to produce ink deposits on said material of predetermined varying densities.

18. In a printing couple, ink carrying means, means for moving print receiving material relative to said ink carrying means and through the printing zone, separate means for producing by electric currents a plurality of separate electrostatic fields of force at the printing zone with the lines of force of said fields of force acting in a direction to transfer ink from said ink carrying means to said material, means for producing magnetic fields of force on each side of said electrostatic fields of force to prevent dispersion of the latter and to confine the same to the printing zone, and separate means movable in correlation to the movement of said material for automatically varying said currents to vary the intensities of each of said electrostatic fields of force as said material moves through the printing zone to produce ink deposits on said material of predetermined varying densities.

19. In a printing couple, a movable member

21

having image portions adapted to be inked, means for moving print receiving material in operative and timed relation to said member and through the printing zone, means for producing by an electric current an electro field of force at the printing zone with the lines of force of said field of force acting in a direction to transfer ink from said image portions of said member to said material, and means correlated to the movement of said material for automatically varying said current to vary the intensity of said electro field of force as said material moves through the printing zone, whereby the ink deposits on said material may be of predetermined varying densities.

20. In a printing couple, a printing member having image portions adapted to be inked, means for moving print receiving material in operative and timed relation to said member and through the printing zone, separate means for producing by electric currents a plurality of separate electro fields of force at the printing zone with the lines of force of said fields of force acting in a direction to transfer ink from the image portions of said member to said material, and separate means movable in correlation to the movement of said material for automatically varying said currents to vary the intensities of each of said fields of force as said material moves through the printing zone, whereby ink deposits of predetermined varying densities can be made on said material.

21. In a printing couple, a movable member having image portions adapted to be inked, means for moving print receiving material in operative and timed relation to said member and through the printing zone, separate means for producing a plurality of separate electro fields of force at the printing zone with the lines of force of said fields of force acting in a direction to transfer ink from the image portions of said member to said material, a master control member movable in timed relation with said movable member and said material, and separate means operatively controlled by said control member for varying the intensities of each of said electro fields of force as said material moves through the printing zone, whereby ink deposits of predetermined varying densities can be produced on said material correlated to said control member.

22. In a printing couple, a movable member having image portions permeable to lines of force and non-image portions impermeable thereto, means for moving print receiving material in operative and timed relationship to said member and through the printing zone by an electric current, means for creating at the printing zone an electro field of force with the lines of force thereof extending through said material and the permeable image portions of said member but intercepted by the impermeable portions thereof and including spaced discharge and attraction elements located in the printing zone on opposite sides of said material and said member, means for introducing ink to said field of force to be carried by the lines of force to areas of said material correlated to said image portions of said member, and means correlated to the movement of said material for automatically varying said current to vary the intensity of said field of force to produce on said material as it passes through the printing zone ink deposits of predetermined varying densities.

23. In a printing couple, a movable member having image portions permeable to lines of force and non-image portions impermeable thereto,

22

means for moving print receiving material in operative and timed relationship to said member and through the printing zone by electric currents, means for creating at the printing zone a plurality of electro fields of force with the lines of force thereof extending through said material and the permeable image portions of said member but intercepted by the impermeable portions thereof and including a plurality of sets of spaced discharge and attraction elements located in the printing zone with the discharge and attraction elements of each set on opposite sides of said material and said member, means for introducing ink to said fields of force to be carried by the lines of force to areas of said material correlated to said image portions of said member, and separate means acting in correlation to the movement of said material for automatically varying said currents to vary the intensities of each of said fields of force to produce on said material as it passes through the printing zone ink deposits of predetermined varying densities.

24. In a printing couple, a movable member having image portions permeable to lines of force and non-image portions impermeable thereto, means for moving print receiving material in operative and timed relationship to said member and through the printing zone, means for creating at the printing zone an electro field of force with the lines of force thereof extending through said material and the permeable image portions of said member but intercepted by the impermeable portions thereof and including spaced discharge and attraction elements located in the printing zone on opposite sides of said material and said member, means for introducing ink to said field of force to be carried by the lines of force to areas of said material correlated to said image portions of said member, a master control member movable in timed relation to said movable member, means for projecting light beams onto said control member to be reflected thereby, light sensitive means activated by the reflected light beams, and means controlled by the degree of activation of said light sensitive means for varying the intensity of said field of force in relation to the strength of the reflected light beams to produce on said material as it passes through the printing zone ink deposits of predetermined varying densities.

25. In a printing couple, ink carrying means, means for moving print receiving material relative to said ink carrying means and through the printing zone, a master control member movable in timed relation to the movement of said material through the printing zone, means for producing an electro field of force at the printing zone with the lines of force thereof acting in a direction to transfer ink from said ink carrying member to said material, means for projecting light beams against said control member to be reflected thereby, light sensitive means activated by said reflected light beams, and means controlled by said light sensitive means for varying the intensity of said field of force in relation to the strength of the reflected light beams to cause ink deposits on said material of predetermined varying densities.

26. In a printing couple, an ink carrying member, means for moving print receiving material relative to said member and through the printing zone, a master control member movable in timed relation to the movement of said material through the printing zone and provided with different areas of predetermined color density,

23

means for producing an electro field of force at the printing zone with the lines of force thereof acting in a direction to transfer ink from said ink carrying member to said material, and means for maintaining the densities of the ink deposits on said material correlated to the color densities of said areas on said control member and including separate means for projecting light beams on said areas of said control member and on said ink deposits on said material to be reflected thereby, separate light sensitive means activated by said reflected light beams, and means controlled by an unbalanced activation of said light sensitive means for varying the intensity of said field of force.

27. In a printing couple, an ink carrying member, means for moving print receiving material relative to said member and through the printing zone, means for producing an electro field of force at the printing zone with the lines of force thereof acting in a direction to transfer ink from said ink carrying member to said material and including an electric circuit, and means for varying the intensity of the current of said electric circuit and hence the intensity of said field of force as said material moves through the printing zone to produce ink deposits on said material of predetermined varying density and including a master control member movable in timed relation to the movement of said material through the printing zone and provided with switch actuating elements arranged thereon in predetermined manner, resistance means adapted to be selectively introduced into said circuit, and switch means actuated by said elements for introducing said resistance means into said circuit.

28. In a printing couple, a rotatable cylinder provided with image portions permeable to lines of force and non-image portions impermeable thereto, means for moving print receiving material through the printing zone and relative to said cylinder with said material supported thereby, a series of discharge blades extending transversely of said material and located on one side thereof at the printing zone, a series of attraction blades located within said cylinder and in the plane of said series of discharge blades with each attraction blade cooperating with a correlated discharge blade to form a plurality of sets of discharge and attraction blades, means for inking said discharge blades, separate means for connecting each set of discharge and attraction blades with a source of high potential electric energy to induce an electrostatic field of force between said blades with the lines of force thereof passing through said material and the permeable image portions of said cylinder and acting to transfer ink from said discharge blade to said material, a master control member movable in timed relation to said cylinder and said material and provided with areas of different predetermined color densities, light sources for projecting light beams onto said areas of said control member to be reflected thereby, light sensi-

24

tive means scanning the control member and receiving the reflected light beams and activated thereby, and means operatively controlled by said light sensitive means for varying the intensities of the fields of force between the sets of discharge and attraction blades to vary the densities of the ink deposits on the print receiving material in correlation to the color densities of said areas on said master control member.

29. In a printing couple as defined in claim 28 and wherein light sources are provided for projecting light beams onto the ink deposits on the print receiving material to be reflected thereby, while light sensitive means scan said deposits and receive the said reflected light beams and are activated thereby, the light sensitive means which scan the control member and the light sensitive means which scan the ink deposits on the material conjunctively controlling the means which vary the intensities of the electrostatic fields of force.

30. In a printing couple, a rotatable cylinder provided with image portions adapted to be inked, a series of radial discharge blades extending longitudinally within said cylinder, means for moving print receiving material through the printing zone and in operative and timed relationship to said cylinder, a similar series of attraction blades located in the plane of said series of discharge blades and on the side of said material remote from said cylinder with each attraction blade cooperating with a discharge blade to form a plurality of sets of discharge and attraction blades, separate means for connecting each set of blades with a source of high potential electric energy to induce an electrostatic field of force between the blades of each set with the lines of force thereof acting in a direction to transfer ink from the image portions of the cylinder to the print receiving material, a master control member movable in timed relation to said cylinder and said material and provided with actuating elements correlated to the sets of discharge and attraction blades and arranged on said control member in predetermined manner, and means actuated by said elements to vary in a predetermined manner the intensities of the fields of force produced by said sets of discharge and attraction blades to effect ink depositions on the material of predetermined varying densities.
